UNITED STATES PATENT OFFICE.

CHAUNCEY W. GAY, OF WEST SPRINGFIELD, MASSACHUSETTS.

COUNTING AND STACKING MECHANISM FOR BOXES.

No. 839,130.

Specification of Letters Patent.

Patented Dec. 25, 1906.

Application filed November 3, 1904. Serial No. 231,294.

To all whom it may concern:

Be it known that I, CHAUNCEY W. GAY, a citizen of the United States of America, and a resident of West Springfield, in the county of Hampden and State of Massachusetts, have invented certain new and useful Improvements in Counting and Stacking Mechanism for Folded Boxes, of which the following is a full, clear, and exact description.

10 This invention relates to means for stacking or bunching productions or manufactures of paper, cardboard, and the like in uniform pluralities, as in bunches all of twenty-five or such other number as may be predetermined, and for thereby effecting a mechanical counting of the pieces.

15 The improvements are particularly adapted for utilization in conjunction with machines for gluing or pasting, folding, and delivering in collapsed and flattened condition, folding boxes or cartons, also in conjunction with envelop - machines and printing-machines.

20 The object is to provide devices for the indicated purpose which are simple reliable in action, unlikely to become deranged in protracted use, and susceptible of combination in unobtrusive manner with the paper-box, envelop, or printing machine in connection 25 with which it is to be employed; and the invention consists in the combination or arrangement of devices and the construction of certain of said devices and of parts thereof, all substantially as hereinafter fully described, 30 and set forth in the claims.

35 The present improved mechanical counting and bunching mechanism is hereinafter described in conjunction with the last operating portion of a paper-box gumming and 40 folding machine which constitutes the subject-matter of an application for Letters Patent of the United States filed by me September 14, 1904, Serial No. 224,441.

45 In the drawings, Figure 1 is a plan view representing the table at which the box-blanks are successively folded, stuck, and flattened and moved to the delivery mechanism and representing the receiving-table for the series of bunches and the mechanical and 50 automatic counting devices. Fig. 2 is an end elevation of the same. Fig. 3 is a vertical sectional view as taken on the line 3-3, Fig. 1, and showing many of the parts in elevation as seen beyond the plane of section. Fig. 4 55 is a perspective view of the most important parts included in the novel mechanism, and

Fig. 5 is a sectional view through the ratchet-wheel and the carrier for the pawl co-operative therewith and showing a friction device or brake for the ratchet-wheel.

60

Similar characters of reference indicate corresponding parts in all of the views.

In Figs. 1 and 3, 75 represents a table on which the blanks are brought in partially-folded condition, as represented at 2 in Fig. 3 and at 47 in Figs. 1 and 2. A slight portion of means for bringing the blanks onto the table 75 through a path at right angles to the length of the table is also shown, and 84 represents the folding wing or blade pivotally mounted near the forward end of a sliding support 81, which has a backward and forward motion as imparted by a swinging lever 91 (cam-operated) in one direction and by the retracting-spring 82 in the other.

75

For a full understanding of the devices as here briefly mentioned for folding and flattening the blanks and also causing the blanks to have movements from left to right, as Figs. 1 and 3 are viewed, for delivery to the bunching and counting mechanism reference may be had to the aforementioned application.

80

The blank the flaps of which have been folded in the manner described will then be subjected to the action of a pair of co-operative pressing-rolls 100 and 101, the former 100 of which is journaled in the stationary bearings held in a pair of auxiliary frames 102, while the latter 101 are mounted in 90 spring-pressed bearings of suitable construction.

85

The blanks are, after being horizontally fed and folded, deposited upon a carton-receiving table with one of their edges resting 95 thereon, and means are provided for diverting the thus far horizontal path of the blank into a vertical one, these means consisting, substantially, of a set of compressing-rolls (designated in a general way by 103 and 104, 100 respectively) and being similar in construction to the rolls 100 and 101 above described and also serving as additional devices for insuring a perfect contact between the flap portions to be united by the previously-deposited layer of gum.

105

The several sets of rolls 100, 101, 103, and 104 are preferably geared together in the manner shown in Fig. 3, in which a gear 160 on the lower roll 100 is illustrated in engagement with a gear 161 for driving the upper roll 103, while another gear 162 drives the

110

lower roll 104, thus preserving the uniform direction of rotary movement for the purpose of advancing the blank in the required manner.

- 5 The initial driving movement is imparted to the lower roll 100 by a chain 163, which drives a sprocket 164, mounted on the shaft of the lower roll 100, and is driven from a sprocket 165, mounted upon a main shaft 12.
- 10 As the folded blank leaves the last set of pressing-rolls 104 it will be dropped vertically onto the carton-receiving table 105, having a sliding weight 106 longitudinally movable thereon and to be gradually forced rearward by the accumulating cartons on the table. Each blank as it drops onto the table will pass and come to rest in front of a pusher 107, (see Figs. 2 and 3,) comprising a horizontally-disposed arm 108, which may be 15 slotted to receive in suitably-adjusted positions thereon one or more pusher-blades 109. The pusher-lever 107 is preferably pivoted on a bracket 110, secured to the frame, and an oscillatory motion is imparted to it by a cam 20 111, secured upon a shaft 12 and moving the thrust-rod 112 in one direction, the spring 112^a insuring the retracting motion, as seen in Fig. 3.
- 25

- The reciprocation of this lever results in 30 the forcing of successive blanks beneath and past a detent 113, pivoted on an angle-bracket 114, secured to the side frame 102, and also forcing the blanks on and past a 35 gravitational detent or by-pass 115, pivoted in the table 105, these by-passes serving to retain the blanks in their pushed-forward position, and therefore avoiding interference with the subsequently-following folded cartons as they are discharged from the rolls 104.
- 40 In conjunction with the delivery portion of the machine last described a counting mechanism is employed whereby one blank will be left projecting beyond the others after a certain number thereof have been 45 deposited on the table. This counting mechanism is shown in all the views, in which it will be seen that a bar 120 is guided by blocks 121, secured to the frame in a suitable manner, and reciprocatory movement is imparted to it by a lever 122, fulcrumed at 123 to the frame and having a roller 124 in engagement with a cam 125, whereby said lever 122 is pushed toward the right, as seen in Fig. 2, while a spring 126 may be employed 55 for moving the bar 120 toward the left. This bar constitutes the medium whereby the successive blanks as they drop upon a table 105 will be pushed from right to left, the particular device for accomplishing this purpose being shown herein as a finger 126', adjustably secured on the bar 120—as, for instance, by screws 127. The right-hand end of the bar 120 has a pin 128, adapted to be engaged by a stop-plate 129, which is secured upon a disk 60 130, made in the form of a ratchet, to which a

step-by-step movement may be imparted by the mechanism to be hereinafter described. In the present instance I have shown the ratchet-wheel as having twenty-five teeth, and during the advance of twenty-four of such teeth the bar 120 may reciprocate with perfect freedom and without meeting any obstruction. At the twenty-fifth tooth, however, the plate 129 will project into the path of the pin 128 during its movement 75 from right to left, as seen in Fig. 4, so that consequently the spring 126 will not have any efficiency in moving said bar. From this it follows that the finger 126' will become inoperative and leave the blank in 80 its original position which it took when dropped on the table—namely, projecting beyond the other cartons which had been previously pushed aside by said finger 126'. Inasmuch as it is essential under the present 85 circumstances that the counting of the cartons shall take place accurately or, in other words, that the counting device shall operate only as blanks are passing through the machine, means are provided for normally retaining the ratchet-wheel 130 inactive, motion being imparted thereto only as a blank is actually passing through the machine. The mechanism employed for achieving this 90 result is clearly shown in Figs. 3 and 4, in which what may be termed a "feeler" 131 is disposed directly in the rear of the rolls 100 and 101. This feeler 131 is mounted upon a spindle 132, pivotally supported on a frame and having a counterweight 133 for normally 95 throwing the lower end of the feeler 131 toward the rolls 101. The spindle 132 is also provided with an arm 134, which is connected, through a link 135, with a pawl 136, pivoted at 137 on an arm or pawl-carrier 138, the pivot-axis of which is concentric with that of the ratchet 130 and which may be operated from an eccentric 139, mounted upon the shaft 12, and connected with said arm by a rod 140 of usual construction. 100

The description just given clearly shows that a constant oscillatory movement will be imparted to the arm 138, while, however, the ratchet-wheel 130 will not be operated unless pawl 136 has been lowered into position by a blank striking the feeler 131, so that a movement of the ratchet-wheel 130 can only result when the blank is passing between rolls 100 and 101. 110

Inasmuch as the present improved mechanisms and appliances are to be employed in conjunction with paper-box machines and the like which are commonly constructed with capabilities for adjustments to accord with different sizes for the products of such machines, capabilities for adjustments of certain of the parts in the present device are shown and will be pointed out as follows: 115

The feeler 131 may have different positions along the length of its supporting-spindle or 120

rocking rod 132 by reason of the provision of the hub portion 131^a and the set-screw 131^b, so that no matter how narrow the folded boxes or blanks may be the feeler may always be positioned in the path of the blank in the delivery movement thereof edgewise onto the receiving-table.

The receiving-table 105 may be raised or lowered in its connection on the main frame 10 of the machine and, as shown, comprises the horizontal table proper and at one end the bracket or brackets 175, depending and having the vertical slots 176, so that with the confining-bolts 177 the vertical positioning of the table may be easily accomplished, while the supporting-leg 178 at the further end of the table may be made of sections having bolt-and-slot confinement, as represented at 179.

In order that the retainers or detents 113 for the flattened boxes or pieces delivered may be positioned properly above the table corresponding to the widths of the boxes, the vertical supporting bars or brackets 114, at the lower ends of which the detents are carried, are, as shown in Figs. 2 and 3, made with the vertical slots 180, so that in conjunction with the confining-bolt 181 the brackets may be vertically adjusted. The brackets, however they may be positioned vertically, are also adjustable horizontally along the girder 102^a of the framing structure 102, which girder has the slot 182, and the same bolts 181 for confining the parts in their vertical adjustments are also utilized for confining them in their horizontally-adjusted positions.

The blades 109, carried on the slotted bar 108, which latter is an angular extension of the lever 107, have their upper portions angular to their lower connected portions, as shown in Fig. 3, so as to form no impediment to the arrival of the blanks from the quadrantly-arranged sets of rolls onto the receiving-table, and the obliquely-disposed upper extremities of the blades may act as guides and also as means for preventing the blanks from tipping downwardly preparatory to their being forced along transversely 50 of the planes of their faces and edgewise resting on the table.

The blade-carrying bar 108, as clearly shown in Fig. 2, is vertically adjustable on the upper extremity of the swinging pusher-lever 107 by reason of the slot 184 and the confining-bolt 185.

In Fig. 5, 188 represents a spring-pressed brake or friction shoe in yielding pressure against the inner face of the ratcheted disk 130, so that there can be no overthrow by momentum of said ratcheted element to result in false counting.

The bearing member is carried at the free extremity of a U-shaped spring having between the opposite members thereof the

spiral spring 190, which is held against displacement on the stud 192.

Having thus described my invention, what I claim, and desire to secure by Letters Patent, is—

1. In a counting device for machines of the character described, comprising a receiving-support for the machine products and means for moving each blank or piece to a position thereupon, a reciprocatory slide operable against the individual blanks, and means for preventing the active movement of said slide once to a given number of movements thereof.

2. In a counting device for machines of the character described, comprising a receiving-support for the machine products and means for moving each blank or piece to a position thereupon, a reciprocatory slide operable against the individual blanks, a rotatable part having a stop member for preventing the active movement of said slide once to a given number of movements thereof.

3. In a counting device for machines of the character described, in combination, a receiving-support for the blanks, rolls through which the blanks are fed toward said support, means for moving each blank laterally of said support comprising a reciprocatory slide, a rotatable ratchet-toothed disk having a stop-plate, a vibrating pawl for intermittently rotating said disk, normally out of engagement therewith, and arranged to become actively co-operative with the ratcheted disk at each passage of the blank through said rolls and past the pawl.

4. In a counting device for machines of the character described, in combination, a horizontal receiving-support for the blanks, pairs of rolls located higher than said support, and in quadrantal, downwardly feeding and deflecting arrangement, through which the blanks are fed from horizontal positions toward said support, coming thereto in vertical positions, means for moving each blank laterally of said support and comprising a reciprocatory slide, a rotatable ratchet-toothed disk, having a stop, a vibrating pawl for intermittently rotating said disk, and normally out of engagement with the ratcheted disk, and arranged to become actively co-operative with such disk at each passage of the blanks through said rolls.

5. In a counting device for machines for paper manufactures, the sets of feed-rolls quadrantly arranged, a receiving-support, a reciprocatory slide for pushing the blanks individually across said support, a rotatable ratcheted disk having a stop, a vibratory pawl co-operating with said ratcheted disk, and normally out of engagement therewith, and a feeler connected to said pawl, and located adjacent said rolls and across the path of the blanks therethrough.

6. In a mechanism of the character de-

- scribed, a pusher and means for positively actuating it (the pusher) in one direction, and yielding means to move it in the opposite direction, a ratchet-wheel arranged adjacent the pusher and having a stop adapted to periodically come to an intercepting position relatively to the pusher, intermittently-operating means for impelling the ratchet-wheel, means for feeding the boxes or blanks, and means controlled by the passage of the blanks and in turn controlling the impelling means for its action and non-action on the ratchet-wheel.
7. In a mechanism of the character described, the sets of feeding-rolls in quadrantal arrangement, as described, and the receiving-table therebelow, a pusher and means for positively actuating it (the pusher) in one direction, and yielding means to move it in the opposite direction, a ratchet-wheel arranged adjacent the pusher and having a stop to periodically come to an intercepting position relatively to the pusher, a constantly-vibrating pawl, a feeler in the path of the roll-feed and having a controlling connection with said pawl and a reciprocatory pusher, having its movements in the line of the receiving-table, and for advancing the blanks thereon.
8. In a mechanism of the character described, the combination with a pair of feeding-rolls and a receiving-table, a pusher-bar arranged for reciprocatory motion horizontally and transversely relatively to the table and having the member 126, and also provided with the stop-pin 128, and the lever 122 engaged with the bar, cam for forcing the lever in one direction and a spring for retracting the lever, of the spindle or rocking rod 132 adjacent, and parallel with, the feed-rolls and having the feeler member 131 supported thereon, and having the counterweight 133 and the lever extension 134, the ratchet-wheel 130 having the stop-plate 129, the pawl-carrier, the pawl 136, a connecting-rod 135 and means for vibrating the pawl-carrier.
9. In a mechanism of the character described, the combination with a pair of feeding-rolls and a receiving-table, a pusher-bar arranged for reciprocatory motion horizontally and transversely relatively to the table and having the member 126' adjustable along the length of the pusher-bar, and also provided with the stop-pin 128 and the lever 122 engaged with the bar, cam-actuated in one direction and spring-retracted, of the spindle or rocking rod 132 adjacent, and parallel with, the feed-rolls and having the feeler member 131 supported thereon, and adjustable along the length of the spindle, and having the counterweight 133 and the lever extension 134, the ratchet-wheel 130 having the stop-plate 129, the pawl-carrier, the pawl

136, a connecting-rod 135 and means for vibrating the pawl-carrier.

10. In a mechanism of the character described, the sets of feeding-rolls in quadrantal arrangement, as described, and the receiving-table therebelow, a pusher and means for positively actuating it (the pusher) in one direction, and yielding means to move it in the opposite direction, a ratchet-wheel arranged adjacent the pusher and having a stop to periodically come to an intercepting position relatively to the pusher, a constantly-vibrating pawl, a feeler in the path of the roll-feed and having a controlling connection with said pawl and a reciprocatory pusher, having its movements in the line of the receiving-table, and for advancing the blanks thereon, and carrying the horizontally-extended bar having one or more up-standing blades located below the down-feeding path of the quadrantly-arranged feed-rolls and having their extremities inclined, as and for the purposes set forth.

11. In a mechanism of the character described, in combination paired feed-rolls and a receiving-table; a pusher and means for positively actuating it (the pusher) in one direction, and yielding means to move it in the opposite direction, a ratchet-wheel arranged adjacent the pusher and having a stop to periodically come to an intercepting position relatively to the pusher, a constantly-vibrating pawl, a feeler in the path of the roll-feed and having a controlling connection with said pawl and a reciprocatory pusher, having its movements in the line of the receiving-table, and for advancing the blanks thereon, and consisting of the lever 107 having the horizontal bar, and one or more blades up-standing from said bar, and horizontally adjustable thereon.

12. In a mechanism of the character described, in combination, paired feed-rolls and a receiving-table; a pusher and means for positively actuating it (the pusher) in one direction, and yielding means to move it in the opposite direction, a ratchet-wheel arranged adjacent the pusher and having a stop to periodically come to an intercepting position relatively to the pusher, a constantly-vibrating pawl, a feeler in the path of the roll-feed and having a controlling connection with said pawl and a reciprocatory pusher, having its movements in the line of the receiving-table, and for advancing the blanks thereon, and consisting of the lever 107 having the horizontal bar vertically adjustable on the lever and one or more blades upstanding from said bar, and horizontally adjustable thereon.

13. In a machine of the character described, in combination, paired feeding-rolls and a receiving-table, a pusher having a stop-pin, and means for positively actuating it

(the pusher) in one direction, and yielding means to move it in the opposite direction, transversely of the table, the ratchet-wheel, having the stop-plate, a constantly-vibrating pawl, a feeler in the path of the roll-feed and having a controlling connection with said pawl, a reciprocatory pusher having its movements in the line of the receiving-table and for advancing the blanks thereon, and 10 detents supported above the table, and vertically adjustable relatively to the table.

14. In a machine of the character described, in combination, quadrantly-arranged pairs of feeding-rolls and a receiving-table therebelow, a pusher having a stop-pin, and means for positively actuating it (the pusher) in one direction, and yielding means to move it in the opposite direction, transversely of the table, the ratchet-wheel having the stop-plate, a constantly-vibrating pawl, a feeler in the path of the roll-feed and having a controlling connection with said pawl, a reciprocatory pusher having its movements in the line of the receiving-table 20 and for advancing the blanks thereon, a cross-frame member having one or more vertical brackets vertically and also horizontally adjustable thereon, and having at their lower portions, above the table, the detents 25 and 30 113, substantially as described.

15. In a machine of the character described, in combination, quadrantly-arranged pairs of feeding-rolls and a receiving-table, comprising vertically-slotted brackets, and having confining bolts whereby it is vertically adjustable on the machine-frame, a pusher-bar and means for positively actuating it (the pusher) in one direction, and yielding means to move it in the opposite 35

direction; a ratchet-wheel arranged adjacent 40 the pusher-bar and having a stop to periodically come to an intercepting position relatively to the pusher, a constantly-vibrating pawl, a feeler in the path of the roll-feed and having a controlling connection with said 45 pawl and a reciprocatory pusher-lever having its movements in the line of the receiving-table, and for advancing the blanks thereon, and provided with the vertically-adjustable slotted bar having the upstanding 50 blade or blades horizontally adjustable on said slotted bar.

16. In a machine of the character described, in combination, the table 75 and the receiving-table therebelow, the paired feed-rolls arranged in parallel arc lines extending from the table 75 forwardly and downwardly toward, but terminating above the receiving-table, a pusher-bar and means for positively actuating it (the pusher) in one direction 55 and yielding means to move it in the opposite direction, a ratchet-wheel arranged adjacent the pusher-bar and having a stop to periodically come to an intercepting position relatively to the pusher-bar, a constantly- 60 vibrating pawl, a feeler in the path of the roll-feed and having a controlling connection with said pawl, and a reciprocatory pusher-lever having its movements in the line of the receiving-table, and for advancing the blanks 65 70 thereon.

Signed by me at Springfield, Massachusetts, in presence of two subscribing witnesses.

CHAUNCEY W. GAY.
